UNITED STATES PATENT OFFICE

165,416

INDICATING INSTRUMENT

Paul S. Dickey, East Cleveland, and Harvard H. Gorrie, Cleveland Heights, Ohio, assignors to Bailey Meter Company, a corporation of Delaware

Application July 22, 1950, Serial No. 11,367

Term of patent 14 years

(Cl. D52—1)

To all whom it may concern:

Be it known that we, Paul S. Dickey, a citizen of the United States, residing at East Cleveland, in the county of Cuyahoga, State of Ohio, and Harvard H. Gorrie, a citizen of the United States, residing at Cleveland Heights, in the county of Cuyahoga, State of Ohio, have invented a new, original, and ornamental Design for an Indicating Instrument, of which the following is a specification, reference being had to the accompanying drawing, forming part hereof.

Fig. 1 is a front perspective view of an indicating instrument, showing the left side and front of our new design.

Fig. 2 is a front elevational view of the instrument.

Fig. 3 is a rear elevational view of the instrument.

The far side of the instrument (not shown) may be similar to the side shown facing the viewer, or may be plain without the screws and screw head recesses.

We claim:

The ornamental design for an indicating instrument, substantially as shown and described.

PAUL S. DICKEY.
HARVARD H. GORRIE.
